CLAIM

The ornamental design for a "U" turn signal indicator lens, as shown and described.

DESCRIPTION

FIG. 1 is a front elevational view of a U-Turn signal indicator lens showing my new design;

FIG. 2 is a rear elevational view thereof;

FIG. 3 is an end elevational view thereof, the opposite end being a mirror image; and

FIG. 4 is a top plan view thereof, the bottom being a mirror image.

FIG. 1

FIG. 2

FIG. 3

FIG. 4
